(57) **CLAIM**

The ornamental design for a cushion for a fence, as shown and described.

DESCRIPTION

FIG. 1 is a perspective view of a cushion for fence embodying my design;

FIG. 2 is a perspective view of the cushion for fence shown in FIG. 1;

FIG. 3 is another perspective view of the cushion for fence opposite that shown in FIG. 2;

FIG. 4 is a plan view of the cushion for fence as depicted in FIGS. 2 and 3;

FIG. 5 is a side elevation view of the cushion for fence as shown in FIGS. 2-4; and,

FIG. 6 is a side elevation view of the cushion for fence opposite that shown in FIG. 5.

The broken lines are directed to environment and form no part of the claimed design.
